UNITED STATES PATENT OFFICE.

ENOTRIO RIENZO SANTONI, OF ANCONA, ITALY.

CONTRACTED OR SHORTENED CHARACTERS FOR PRINT.

Application filed March 24, 1921. Serial No. 455,811.

To all whom it may concern:

Be it known that I, ENOTRIO RIENZO SANTONI, school teacher, a subject of the King of Italy, and residing at Ancona, Italy (whose post-office address is 11 Via del Comune, Ancona, Italy), have invented certain new and useful Improvements in Contracted or Shortened Characters for Print, of which the following is a specification.

10 The object of my present invention is to provide contracted characters for print the main feature of which consists in that one fundamental or primary letter, such as for instance the first or initial letter of a syllable, has the other letters of the syllable so embodied or merged in, or annexed to itself, that the entire syllable forms but one character or symbol, or at the most two characters or symbols, the said secondary letters being embodied into the primary ones 20 in a reduced or symbolized shape, or annexed to the primary ones by superposition, equally in a reduced or symbolized shape.

In the annexed sheet of drawing four 25 brief sentences in the German, French, English and Italian languages are represented in contracted print according to the invention in one of its modifications by way of example.

30 As is seen, each line of print formed by my improved contracted characters is therefore, so to say, two storied, comprising a first story or degree of fundamental letters with the secondary ones embodied or merged 35 therein, and an upper or second story or degree comprising the overhead or mobile letters or symbols, the latter also comprising reduplication or "gemination," inversion and blank symbols or "spaces," as well as 40 accents and other diacritical signs.

My present invention aims at a substantial economy of time and labour in the composition, and space, meaning paper, in the printing.

45 It is obvious that my above said fundamental idea of shortening print by contracting two or more letters into one, both by embodying and superposing may be realized or carried into practice in various 50 ways.

In the modification hereinafter described I have chosen the Roman characters as a departure for my new contracted print.

55 In forming my "fundamental" characters I have availed myself of the notion that in each of the Roman characters a main or

characteristical part may be distinguished from more accessory or subordinate parts. The main feature of "a" for instance is the square $\square$ at the bottom, of "e" the crescent $\smile$ at the top, of "i" the dot $\circ$, of "o" the lower half circle $\smile$, and of "u" the parallel lines which for convenience may be used in a horizontal position: =

These vowels thus reduced or symbolized 65 are inserted or merged into the body of the consonants so as to form short syllables contracted to a single character or symbol, which means an economy of space of 50%, for instance:

ba = b , be = b , bi = b , bo = b , bu = b

ca = c , ce = c , ci = c , co = c , cu = c

and so forth.

In the case of the consonants not forming 75 the initial letter of the syllable but one of the inner letters of same, they may be expressed as follows:

The characteristic or main feature of "l" 80 for instance being a straight line, I insert same in a slightly inlined position in the contracted syllables:

bla = b , ble = b , bli = b , blo = b , blu = b

cla = c , cle = c ,cli = c , clo = c , clu = c

85 and so forth.

As the main feature of "r" I take the lateral hook or crotchet $\nearrow$ and insert same in this symbolized shape into the contracted 90 syllables, as follows:

bra = b , bre = b , bri = b , bro = b , bru = b

cra = c , cre = c , cri = c , cro = c , cru = c

95 The consonant "n" is mainly characterized by a horse shoe open to the bottom $\square$, and is inserted in this symbolized shape into the syllables, for instance as follows:

gna = f , gnu = f

100

and so forth.

By thus merging the three liquids "l," "r," and "n" into the initial consonants of simple syllables I realize an economy of time and space of $\frac{1}{2}$ in the composition of the 105 print.

In the combinations qua, que, qui, and quo the "u" is always the central letter so as to exclude any doubt as to its position, so that the symbols:

a e c and g

110

must by necessity be read: qua, que, qui, and quo.

As main feature of "h" I take the long vertical stroke and insert same into the syllables in vertical position in order to distinguish it from the inclined stroke of "l", in the following manner:

ch = $\mathcal{C}$, che = $\mathcal{C}$, ghe = $\mathcal{C}$

10 as distinguished from

cle = $\mathcal{C}$ gle = $\mathcal{C}$

The symbols or characters of my new system are of the height of the short letters of the Roman minuscules "a" "c" "e" "i" "m" "n" "o" "r" "s" "u" "v" "w" "x" "z," for instance

b = b, d = $\mathcal{C}$, p = b, g = G

20 Capitals are distinguished from minuscules by an asterisk *, thereby doing away with the whole majuscule alphabet.

All of the above described letters according to the chosen modification or example of my improved system are "fundamental" letters, as distinguished from the superposed "overhead" or mobile symbols, which latter form the "upper story" or second degree of a print line according to my invention, so that each "fundamental" letter, or letter of first degree, has superposed to it an "overhead" letter or symbol. Where there is no letter to be superposed to a fundamental letter the space in the composition is filled with a "blank" type, so as to prevent the composition or "matter" from becoming loosened. The "overhead" letters are symbolized shapes or contractions of the alphabetical letters, as has been described for instance for the vowels a = $\square$, e = $\cap$, i = $\circ$, o = $\smile$, u = $\equiv$, whilst the consonants "l" "m" "n" "r" "s" as overhead letters may be expressed by the following symbols: l = $\overline{\smile}$, m = $\overline{\square}$, n = $\overline{\cap}$, r = $\overline{\circ}$, and s = $\overline{\equiv}$. The liquids "l", "m", "n", "r" when used as overhead letters are read in the spelling after the fundamental letters to which they are superposed, whilst all the other overhead letters are read before the fundamental letters to which they are superposed. In the case, however, of their being intended to be read after the fundamental letter or letters to which they are superposed, they are distinguished by a small arrow pointing to the right: $\rightarrow$, such as for instance:

sga = $\mathcal{C}$, but gas = $\mathcal{C}$

As a sign of reduplication or "gemination" of the fundamental letter an overhead symbol such as $\vee$ is used, for instance

Gatte = * $\mathcal{C}$ $\vee$

and as a sign that the fundamental letters to which it is superimposed should be read in-

verted, so that the vowel, instead of being read after, is to be read before the consonant, an overhead symbol such as $\wedge$ is used, for instance:

bo = $\mathcal{O}$, but ob = $\mathcal{O}$

At last among the overhead symbols are also the usual accents $\acute{}$ $\grave{}$ $\circ$ and the quotation marks or inverted commas " " in their usual shapes.

In the case of more than one overhead symbol to be superposed to a fundamental letter one of them is placed in the blank or space between two words, for instance:

square = $\mathcal{C}$, sgral = $\mathcal{C}$

By superposing a consonant as overhead letter to another consonant as fundamental letter, such as for instance:

zm = $\mathcal{M}$, zl = $\mathcal{Z}$, lr = $\mathcal{Z}$

and so forth, 50% of space is economized.

As a further abbreviation two overhead letters may be fused, such as for instance:

lr = $\mathcal{Z}$, ls = $\mathcal{L}$, nm = $\mathcal{M}$, mn = $\mathcal{W}$

and so forth.

It is understood that my above described contracted print is not intended to thoroughly replace or substitute the usual print, but only to be used in cases where it is desirable to have small handleable books or pamphlets such as pocket editions of scientific handbooks, guides and such like. The letters t, q and z are expressed by the symbols t = T, z = Z.

By way of example and as a proof that and how my contracted print may be used for the four principal languages a sentence in each of them has been reproduced in the annexed drawings, namely

In English: "Under the reign of Edward the Fourth of England"

For German: "Dem Schwachen ist sein Stachel auch gegeben"

For Italian: "Nel mezzo del cammin di nostra vita"

For French: "Cette obscure clarté qui tombe des étoiles,"

but it is obvious that my new system may also be applied to Slav or other languages.

Having now fully described my said invention and the manner in which the same is to be performed;

I claim:

1. Contracted character for print, comprising, in combination, a fundamental letter, symbolized secondary letters inserted in same, and symbolized mobile overhead letters superposed to same, such as described and illustrated.

2. Contracted character for print such as described, comprising, in combination, a fundamental letter taken from the Roman alphabet, symbolized secondary letters taken

from the Roman alphabet, inserted into the said fundamental letter, and symbolized mobile overhead letters taken from the Roman alphabet, superposed to the said fundamental letter, such as described and illustrated.

3. Contracted character for print such as described, comprising, in combination, a fundamental letter, symbolized secondary letters inserted in same, symbolized mobile overhead letters superposed to same, and

overhead symbols for reduplication and inversion of the fundamental letters to which they are superposed.

In testimony whereof I have hereunto signed my name in the presence of two witnesses.

ENOTRIO RIENZO SANTONI.
